YARN TENSION SYSTEM

Hans J. Theiler, Whitinsville, Mass., assignor to
 Whitin Machine Works, Whitinsville, Mass., a
 corporation of Massachusetts

Application December 29, 1942, Serial No. 470,524

7 Claims. (Cl. 242—154)

The invention is an improved yarn tension system, of the creel-mounted type for use in multiple-head yarn-winding machines, the purpose being to simplify the process of adjusting the winding tension so that it can be effected individually and simultaneously in all of the yarns by minute and exactly equal increments as to each, thereby saving much delay and labor heretofore required for this operation.

To this end the invention consists in the organization of parts and in their respective related functions as herein explained and exemplified in the drawings wherein

Fig. 1 is a partial end view of an automatic yarn-winder.

Fig. 2 is a side elevation of the new tension system.

Fig. 3, a plan of Fig. 2.

Fig. 4, a larger scale plan of one tension group.

Fig. 5, a side elevation thereof partly in section, and

Fig. 6, an end elevation.

In Fig. 1 the automatic winder, denoted generally by 1, has an upstanding creel at its rear comprising uprights 2 supporting horizontal, forwardly extending arms 3, including also such longitudinal and cross bracing as may be appropriate. The new system is mounted on the front ends of these arms 3, above the winding mechanism. The yarns are drawn through it from the creel packages 4 by the rotating bobbins 5 on which the yarns are wound and, as will be understood, the tension imparted to the yarn controls the firmness of the woven product. There are commonly many winding heads in a winding machine all arranged in a row on a common base, and all served from the yarn-packages or the creel mounted on such base.

The new system comprises two horizontal parallel shafts 6 and 7, of square section in the present case, both running the full length of the creel, which is to say, the full length of the machine. These shafts are preferably mounted one above the other or at least close together, and one of them, which is the lower one in the present case and marked 7, is fixed rigidly to the creel arms 3 by means of a series of hangers 8 sleeved on the arms 3 (Fig. 2) and secured fast thereto, thus making this lower shaft 7 a part of the creel framing, being parallel to the row of winding heads 5, and above them.

The upper shaft 6 which can be supported directly or indirectly, by the same hangers 8, is endwise movable with respect to them for the purpose of tension adjustment, as presently explained and such movement in the present case is conveniently accomplished by rotating the wheel nut 9 that is threaded to one end of this shaft adjacent to a hanger 8 as shown at the right hand end of Fig. 2. The adjustment is locked

and made permanent by setting up a companion nut 10 threaded on the shaft, on the opposite side of the same hanger. Since this adjustment controls the tension for the whole machine, it is found desirable to bolt a cover 11 over the wheel nut 9 to guard against inadvertent or unauthorized operation of it which might have serious consequences on the wound product.

For each of the winding heads in the row there is a group of tension units for controlling the tension of the yarn going to that head. There is no limitation to the particular design of the tension unit but the style best suited to the purposes of this invention comprises two superposed disc elements 12 and 13, dished so as to have divergent rims, each pair of discs being mounted on a vertical post element 14 which is desirably a porcelain sleeve capable of rotation on a stud shaft 15, the free end of which shaft is bent over and inwardly so as to serve as a slope to guide the yarn between the discs, as a convenience in threading up. The porcelain sleeve and the lower disc rest on soft washers.

Such tension units are by themselves well known in the art and need not be described further than to say that the yarn passing through them rubs on the discs and also on the porcelain sleeves or posts, and the rubbing friction creates the tension. Some rotation is thereby imparted to the sleeves and discs, by the movement of the yarn, but the tension-producing friction is primarily that of the yarn rubbing on these elements.

One part of the group of tension units for each head, two units in the present case, is mounted on or fixed to the fixed shaft 7 of the creel framing, approximately directly over its winding head, and the other part of the group, one unit in the present case, is connected to or mounted on the movable shaft 6, all units being in the same horizontal plane. The yarn is threaded successively around each unit of the group so that the tension is the sum of the frictional effects of the whole group of units. Such tension is changed by changing the relative positions of the two parts of the group which changes the extent of friction surface engaged by the yarn, and which is done by endwise shifting the rod 6.

The two fixed units are shown as mounted by their respective studs 15 on the opposite ends of a horizontal fixture or brackets 16, which is secured to the shaft 7 by a set screw 16a, and the entrance guide 11 and the exit guide 18, are also mounted on this bracket. The guide 18 is a porcelain button and the end of the bracket to which it is fixed is formed with a horn 19 serving as a slope to direct the yarn onto it when threading up. Such brackets, rather than the hangers 8, also form the slideway bearings for the movable shaft 6, each being for this purpose provided with a recess on its upper side, between the two units,

in which the rod 8 slides and to which it is confined by a strap 21 (Fig. 4).

The movable tension unit of the group is mounted by its stud 15 directly on the upper face of such movable shaft 6 and in the same horizontal plane as the two other units, and has a supplementary yarn-guiding slope 6* also fixed directly to the shaft. It is the middle unit and when it is moved close to the line between the other two, to the left in Fig. 6, the friction of the yarn, and hence the tension thereof, is least, when moved away from such line to the right, it is maximum, the difference being due to the change thus caused in the length of the total length of surface over which the yarn rubs in passing around the units.

Thus by endwise moving the shaft 6, as by manipulating the wheel unit 9, the yarn tension can be simultaneously changed for all of the winding heads.

The tension in each individual head can be changed independently of the others by appropriately shifting the normally fixed position of its bracket 16 on the shaft 7, that is to say, by the use of the screw 16* above referred to. Close equality of tension as between all the heads can thus be easily obtained and thereafter extremely fine and simultaneous adjustment for all of the heads can be quickly made, by the use of the wheel nut thereby insuring that whatever the grade of the yarn the machine will produce an identically wound product on all its bobbins and spindles.

The close proximity and vertical relation of the two shafts 6 and 7 afford the opportunity to furnish the system with a simple indicator whereby the extent or value of any change of adjustment may be observed or checked. This consists of a window-plate 20 or the like, fixed fast to the lower shaft 7, overlying the movable shaft, and marked with a scale or index for comparison with an index or scale placed on the latter, showing through the window. By this means any degree of tension known to be appropriate for a particular kind of yarn can be established at once for all the heads and without the customary preliminary testing, head by head.

I claim:

1. A tension system for a multi-head winding machine, comprising a creel at the rear of such machine including forwardly extending arms overlying the winding mechanism of the machine, hangers carried on the front ends of such arms and a horizontal shaft carried on and fixed to said hangers, a group of tension units for each winding head, a part of each such group being normally fixed on said horizontal shaft, a movably mounted companion shaft on such creel common to all of said tension groups, the other part of each of said tension groups being connected to such movable shaft and subject to simultaneous equal adjustment with relation to the normally fixed units by the movement thereof.

2. A tension system for a multi-head winding machine, comprising a creel at the rear of such machine, and two horizontal shafts carried by said creel, one of them being endwise movable therein, a group of tension units for each winding head, a bracket for supporting a part of each such group, said bracket being normally fixed to but longitudinally adjustable on one of said shafts to change the position of the tension units

thereon, all of the remaining part of each tension group being carried on the other of said shafts whereby all of the tension groups are adjustable independently and collectively.

5 3. A tension system for a multi-head winding machine, comprising a creel on the rear of such machine and two horizontal shafts carried on said creel one above the other and above the machine, a group of substantially horizontal tension units for each winding head, a part of each such group being mounted on one of said shafts, a bracket mounted on the other shaft carrying the other part of said tension groups and supporting said other part in a common plane with the rest of the tension group and means for endwise moving one of said shafts.

4. A tension system for a multi-head winding machine, comprising a creel at the rear of such machine and two horizontal shafts carried on said creel one above the other and above the machine, a group of tension units in a substantially horizontal plane for each winding head, a part of each such group being mounted on one of said shafts, a bracket mounted on the other shaft carrying the other part of each of said tension groups and supporting said other part in the same plane as the rest of the tension group, said bracket being longitudinally movable on its shaft, and means for endwise moving one of said shafts.

5. A tension system for a multi-head winding machine, comprising a creel at the rear of such machine and two horizontal shafts carried on said creel one above the other, a group of tension units in a substantially horizontal plane for each winding head, a part of each such group being mounted on one of said shafts and said shaft being endwise movable, a bracket mounted on the other shaft carrying the other part of each of said tension groups, said bracket forming a support for the endwise movable shaft, and means for endwise moving said other shaft.

6. A tension system for a multi-head winding machine, comprising a creel at the rear of such machine including forwardly extending arms, hangers carried on the front ends of such arms and a horizontal shaft carried on and fixed to said hangers, a group of tension units for each winding head, a bracket adjustably mounted on said fixed shaft, a part of each tension group being mounted on said bracket, a companion horizontal shaft movably supported on said brackets, the other part of each of said tension groups being connected to such movable shaft and subject to simultaneous adjustment with relation to the normally fixed units by the movement thereof.

7. A creel-supported tension system for a multi-head winding machine, comprising a creel at the rear of such machine, a horizontal shaft carried on said creel, a substantially horizontal group of tension units for each winding head, a bracket on said shaft, two units of each tension group being mounted on said bracket, an endwise movably companion shaft on such creel common to all of said groups, another unit of each of the tension groups being mounted on such movable shaft respectively, intermediate of said other units and subject to simultaneous equal adjustment with relation thereto by the endwise movement of said companion shaft.
